UNITED STATES PATENT OFFICE.

MARGARET SMITH, OF OWEN SOUND, ONTARIO, CANADA.

WINDOW SCREEN.

Application filed September 5, 1922. Serial No. 586,297.

To all whom it may concern:

Be it known that I, MARGARET SMITH, a citizen of the Dominion of Canada, and resident of Owen Sound, in the county of 5 Grey and Province of Ontario, Dominion of Canada, have invented certain new and useful Improvements in Window Screens, of which the following is a specification.

This invention has relation to certain 10 new and useful improvements in window screens and has for its primary object the provision of sectional adjustable window screens which may be readily applied and left in the window frame without interference with operation of the inner or lower 15 sash.

The invention has for another object the provision of adjustable window screens of the character stated which may be adjusted 20 transversely and vertically without separation of the screen section so as to permit flies and the like to pass through the window.

Another object of the invention resides in 25 the provision of adjustable window screens of the character stated which will be composed of the minimum number of parts of simple construction and arrangement and which may be readily adjusted, as desired.

30 A still further object of the invention resides in the provision of adjustable and sectional window screens of the character stated which may be readily adjusted in the supporting members provided for mounting the screens in the window frames 35 opposite one of the adjustable window sashes.

Still another object of the invention resides in the provision of sectional adjustable window screens of the character stated in 40 which the sections will be of special construction so as to securely retain the edges of the wire mesh members in the retaining edge members of the sections and these various sections held by the supporting 45 members in close overlapping relation so as to prevent flies and the like from passing in or out of the window between the screen sections.

With the foregoing and other objects in 50 view as will appear as the description proceeds, the invention consists in the novel construction, combination and arrangement of co-operating elements as hereinafter more specifically set forth, claimed and 55 shown in the accompanying drawings form-

ing a part of the present application in which:

Fig. 1 is an elevation of the lower portion of a window with the improved window screen in use and showing the sections in 60 their extended positions.

Fig. 2 is an enlarged detail fragmentary perspective view of the screen, showing the manner of overlapping the sections thereof.

Fig. 3 is an enlarged fragmentary horizontal section substantially on the plane of line 3—3 of Fig. 1, looking in the direction indicated by the arrows.

Fig. 4 is an enlarged fragmentary detail perspective view of a corner of one of the 70 sections to disclose the construction thereof.

Fig. 5 is an enlarged fragmentary elevation of one of the supporting and guiding members, showing the manner of mounting the same.

Fig. 6 is a fragmentary vertical section substantially on the plane of line 6—6 of Fig. 5, looking in the direction indicated by the arrows.

Referring more in detail to the drawings 80 in which similar reference characters designate corresponding parts throughout the several views, 10 designates the window sill, 11 a sliding window sash and 12 the side frame members of a window to which the 85 improved window screen is adapted.

In constructing the window screen the supporting and guiding members 13 are employed and mounted vertically in the side frame members 12 between the beads or 90 guide strips 14 for the sliding window sash 11. When the screen is mounted as shown in the drawings, the supporting and guiding members 13 are positioned beneath the upper or outer sliding window sash 11. Each 95

supporting and guiding member 13 is composed of a metallic plate bent to form an outwardly directed central rib 15, after which the sides of the plate are bent outwardly and then toward one another to cooperate with the outwardly directed central rib 15 in forming parallel guide pockets 16 of rectangular form in end elevation and extending practically the entire length of the supporting and guiding member 13. 105 The parallel guide pockets 16 are both open along their meeting longitudinal inner corner 16' opposite the edge of the outwardly directed central rib 15, as shown clearly in Figs. 3 and 5. At either end of the support- 110

ing and guiding members 13 the ends of the plates from which the supporting and guiding members 13 are formed are left flat and extended a short distance to either side to 5 form the ears 17 having elongated slots 18 provided therein and through which the securing screws 19 are extended, these securing screws 19 having heads 20 which are turned across the elongated slots 18 to retain the 10 supporting and guiding members 13 in position. When it is desired to remove the supporting and guiding members 13, it is simply necessary to give the securing screws 19 a quarter turn to bring the heads 20 thereof 15 into registration with the elongated slots 18 and then lift off the supporting and guiding members 13. These supporting and guiding members 13 may be just as readily mounted on the securing screws 19 and the 20 securing screws 19 then turned to bring the heads 20 thereof across the elongated slots 18.

Each screen section comprises a rectangular body 21 of fine wire mesh or other 25 suitable material. The upper and lower edges of the rectangular body 21 are secured in the upper and lower frame members 22 which are formed of narrow metallic strips 30 bent upon themselves longitudinally and centrally and clamping on opposite sides of the upper and lower edges of the wire mesh composing the rectangular body 21. This may be readily understood by referring to Figs. 2 and 4. The inner vertical edge of 35 each screen section is also formed of a frame member 23 corresponding to the upper and lower frame members 22, with the exception that the ends of the frame members 23 are extended and bent upon themselves in rectangular form to produce the rectangular guides 24 for the upper and lower frame members 22. It is to be understood that the 40 upper and lower frame members 22 of each screen section slide through the rectangular guides 24 of the overlapping screen section with which the first mentioned screen section 45 is adjustable transversely of the window. This should be apparent by reference to Fig. 2 as well as Fig. 1.

50 In order that the overlapping screen sections may be adjustable vertically of the window, each screen section has an outer end frame member 25 within which the outer vertical edge of the rectangular body 21 of 55 the screen section is secured. The outer end frame member 25 is composed of a pair of solid members of triangular form in end elevation and placed with their wide flat faces opposite to one another and on opposite sides 60 of the rectangular body 21, after which the securing members 26 are passed through the triangular members and through the rectangular body 21 from the opposite edges of said members, as shown in Fig. 4. It will 65 therefore be seen that the complete outer

end frame member for each screen section is of rectangular form in end elevation and by reference to Fig. 3 it will be seen that each outer end frame member 25 is arranged for adjustment in one of the parallel 70 guide pockets 16 of the supporting and guiding members 13. In order to retain the screen sections in their adjusted positions vertically of the window, set screws 27 are threaded in the walls of the parallel guide 75 pockets 16, near the open longitudinal inner corners 16' thereof. It is evident that these set screws 27 may be tightened to press apart the outer end frame members 25 within the parallel guide pockets 16 and thereby 80 prevent sliding movement of the outer end frame members 25 in the parallel guide pockets 16. For the purpose of raising and lowering the screen sections when the set screws 27 are loosened, each screen section is 85 provided with a lifting hook 28 either above or below the supporting and guiding members 13, according to the position of the screen section and the guide pockets 16 within which the screen section slides.

90 It is believed the complete construction and operation of the screen may now be clearly understood from the foregoing paragraphs taken in connection with the accompanying drawings without further detail 95 description. It may be briefly stated, however, that the supporting and guiding members 13 may be readily positioned on the side frame members 12 of the window to which the screen is to be applied and the 100 screen sections connected in pairs, as shown in Figs. 1 and 2 for adjustment transversely of the window and then the pairs of screen sections mounted in the supporting and guiding members 13 for adjustment vertically of the window, as previously described and as clearly shown in Fig. 1. The screen, when properly adjusted, will extend downwardly to the window sill 10 and upwardly to the sliding window 110 sash 11 beneath which the screen is positioned as well as projecting to either side of the window frame. The close engagement of the overlapped edges of the screen sections will prevent flies or the like from 115 passing through the window between the screen sections. It is therefore evident that a simple and inexpensive form of sectional adjustable screen is provided which may not only be readily mounted in the window 120 frame and removed but will also be highly efficient in use. When not required for use, the screen may be stored away in compact form with the screen sections practically parallel to one another or disconnected and 125 removed from the supporting and guiding members 13.

130 While the preferred embodiment of the invention has been disclosed, it is to be understood that minor changes in the de-

tails of construction, combination and arrangement of co-operating elements may be resorted to within the scope of what is claimed without departing from the spirit 5 of the invention.

What I claim as new is:

1. An adjustable sectional screen comprising supporting and guiding members formed with parallel pockets extending longitudinally thereof; said supporting and guiding members being adapted for detachable mounting on a window casing; screen sections arranged in transversely adjustable pairs; said pairs of screen sections being 10 adjustable in said supporting and guiding members, whereby the screen may be adjusted vertically of the window; and means 15 for securing said screen sections in their vertical adjusted positions within said supporting and guiding members.

2. An adjustable sectional screen comprising supporting and guiding members adapted for detachable mounting on a window casing; said supporting and guiding members being formed with parallel pockets of rectangular form in end elevation and having a common opening at their inner connecting corners; screen sections arranged in upper and lower pairs having 20 their meeting vertical edges overlapped whereby said sections may slide upon one another; said sections having outer vertical frame members arranged for sliding engagement in said pockets of the supporting and guiding members; said upper and lower pairs of screen sections being adjustable vertically of the window and independently of one another; and means for securing said pairs of screen sections in adjusted 25 position within said supporting and guiding members.

3. An adjustable sectional screen com-

prising screen sections of rectangular form; the lower portion of said screen sections carrying guide members at their upper 45 edges, whereby said sections may slide transversely of one another for adjustment across a window; supporting and guiding members adapted for detachable mounting in a window frame to support the screen 50 sections in alignment with one of the window sashes; said supporting and guiding members having a central rib with pockets on opposite sides thereof; said screen sections being mounted in pairs in said pockets 55 and adapted for adjustment vertically of the window to bring the upper and lower pairs of screen sections into engagement with the window sill and the window sash; lifting hooks carried by said screen sections; and means carried by said supporting and guiding members for retaining the pairs of screen sections in their vertically adjusted positions.

4. In an adjustable sectional screen, a 65 supporting and guiding member embodying a plate bent to form a central rib and then outwardly and then at angles to form parallel guide pockets upon opposite sides of said rib with their adjacent edges spaced 70 opposite said rib.

5. In an adjustable sectional screen, a supporting and guiding member embodying a plate bent to form a central rib and then outwardly and then at angles to form parallel guide pockets upon opposite sides of 75 said rib with their adjacent edges spaced opposite said rib, and outer frame members each composed of a pair of members of triangular form engaged in said guide 80 pockets.

In testimony whereof, I affix my signature.

MARGARET SMITH.
